SUPPORTING AND CONTENT DISPENSING
ATTACHMENT FOR COLLAPSIBLE TUBESDonald E. Marshall, Summit, N. J., assignor to
Colgate-Palmolive-Peet Company, Jersey City,
N. J., a corporation of Delaware

Application March 30, 1944, Serial No. 528,723

4 Claims. (Cl. 222—424.5)

1

This invention relates to the art of dispensing and is more particularly concerned with attachments designed to adapt conventional collapsible tubes to meet particular dispensing requirements in connection with differing types of cosmetics and the like.

While collapsible tubes of conventional design have been widely used for the retail packaging of articles such as tooth paste, shaving cream, deodorant cream, salves and medicinals of various sorts, it is apparent that the usual round discharge opening is not the most suitable type of dispensing aperture for all types of cosmetics and medicinals but is rather a compromise arrangement adaptable, with some inconvenience to the user, to a large number of dispensing operations widely differing in basic requirements. For example, tooth paste and shaving cream are normally dispensed onto brushes although the brushes used in the two instances widely differ in size and construction. Deodorant creams and medicinals, on the other hand, are usually dispensed to the fingers for daubing, while some medicinals require direct application to the part of the body to be treated.

In an effort to adapt collapsible tubes to a particular use, several unique designs have been devised each, however, inherently limited to meet the dispensing requirements of but a single cosmetic or medicinal. Specialized tubes of the foregoing type, while affording the desired convenience for the user, are not particularly satisfactory from the point of view of the manufacturer due to the fact that the economies inherent in the mass production of a single design are lost, the manufacturer requiring a distinct model for each type of preparation to be marketed.

It is therefore an object of this invention to solve the foregoing problems by providing attachments for a single type of collapsible tube which will render it adaptable to a wide variety of dispensing requirements, thus retaining the advantages of mass production of a single type tube without loss of the convenience and sales appeal inherent in the provision of a dispensing tube specifically designed for use with a particular article.

According to this invention it is contemplated that attachments, individually designed for convenient dispensing of a particular article, be provided with a common means for attachment to the discharge spout of a conventional collapsible tube.

A further object of this invention is the provision of attachments of the foregoing types in

2

which the tube seal is well maintained by a convenient auxiliary cover which additionally serves as a supporting base for the tube which may be inverted for storage when not in use, thus overcoming the inconvenience of replacing the tube screw cap.

Other objects and advantages of this invention will be apparent from a consideration of the following detailed description of several embodiments thereof in conjunction with the annexed drawings, wherein:

Figure 1 is a view partially in elevation and partially in vertical section of a conventional collapsible tube with a novel dispensing attachment for tooth paste attached thereto, the closure cover being shown in operative position;

Figure 2 is a view in section taken on the line 2—2 of Figure 1;

Figure 3 is a view in section taken along the line 3—3 of Figure 1;

Figure 4 is a view in elevation illustrating the inverted storage position of the tube and attachments of Figure 1;

Figure 5 is a view similar to Figure 1 but illustrating an attachment designed for use in the dispensing of deodorant creams and the like;

Figure 6 is a view also similar to Figure 1 but illustrating an attachment designed for use in the dispensing of shaving cream; and

Figure 7 is a view in section taken along the line 7—7 of Figure 6.

Referring to Figures 1 to 4, inclusive, in greater detail, the numeral 10 designates a collapsible tube of conventional design having at its upper end the usual frusto-conical end wall 11 and threaded boss 12 defining the usual cylindrical discharge opening.

A spout member 13, having a concave frusto-conical lower surface conforming to the shape of end wall 11 of the tube and in coextensive direct engagement therewith, constitutes one of the principal parts of the attachment of this invention. This member 13 is provided with a central interiorly threaded aperture at 14 adapted to engage the exterior threads of boss 12 so that spout member 13 can be held in the position shown in Figure 1. Surrounding spout member 13 is an annular sleeve 15 having an integral backing member 16 depending therefrom along the length of tube 10. Sleeve 15, as illustrated in Figures 1 and 3, thus provides a skirt on spout member 13 surrounding a portion of tube 10 adjacent end wall 11.

Fitting over sleeve 15 and the top of spout member 13 is an exteriorly cylindrical cap 17

having an interior face exactly conforming to the contours of spout member 13 so as to seal the central aperture thereof at 14. As illustrated in Figures 1 and 3, the contacting lateral surfaces of cap 17 and spout member 13 are frusto-conical so that the sealing fit between them is broken upon even slight outward displacement of cap 17.

The portions of spout member 13 defining the central aperture above the threaded portion are so shaped as to define a diametrically extending enlarged surface recess 18 surrounding the outer end of the passage defined by aperture 14 and of a width and length suitable for the reception of the bristles of a tooth brush, see Figure 2. The recess at 18 coacts with the adjacent surface of the closure member to define a dispensing chamber, in registry with the aperture at 14 so that tooth paste may be supplied to the recess by compression of the collapsible tube which will cause the formation of a small body of tooth paste in the center of the recess at 18. This body is then distributed as the brush is passed through the recess, adhering to the bristles uniformly so that by the same operation the recess is cleaned and the bristles of the tooth brush are coated with paste. After such an operation, using recess 18, friction cap 17 may be replaced to the Figure 1 position and the tube inverted for storage to the Figure 4 position so that the top surface 19 of the cap may serve as a base for the tube and accessory assembly when not in use.

In view of the provision of rigid integral backing member 16, tube 10 may be collapsed uniformly from bottom to top as the paste within it is used, the backing being constructed of a hard material permitting the tube to be smoothly compressed thereagainst to avoid waste of the contents and wrinkling of the tube.

While there are many materials from which spout member 13, cap 17, sleeve 15 and backing 16 may be made, it has been found that hard plastics such as lucite or phenol formaldehyde condensation products present an attractive appearance and are of suitable hardness. Since the cap 17 is to be used as a base for the tube when the latter is not in operation, it may be desirable to make it of a heavier material or to weight it in some way to insure against accidental upset in storage.

In Figure 5 an attachment of the type adapted for use in connection with cream type deodorants is illustrated. The tube is exactly the same as that illustrated in Figure 1 and the parts thereof have been designated by like reference characters. In this instance, however, the spout member 20 is a unitary element which is generally exteriorly cylindrical. The lower portion of spout member 20 defines an annular flange or skirt 21 adapted to surround the upper portion of tube 10 adjacent frusto-conical end portion 11 thereof. Above annular flange 21 the frusto-conical interior defining walls of spout member 20 converge inwardly conforming to the configuration of end wall 11 of tube 10 with which they are in direct engagement and terminating in a central cylindrical aperture at 22 having a threaded portion at 23 adapted to engage the threads of boss 12 of tube 10. As is the case in connection with the form of invention illustrated in Figure 1, when spout member 20 is screwed into the operating position it is firmly held by the engagement between threaded area 23 and the threads on boss 12 while the depending sleeve or skirt 21 and the portions directly engaging the end wall 11 of the tube hold the spout portion against angular movement tending to dis-

tort the end wall of the tube or to break off the threaded boss at its base.

Above the aperture at 22 the interior 24 of the spout member 20 is cup-shaped, the frusto-conical walls diverging slightly from bottom to top as viewed in Figure 5. Into the cup-shaped socket at 24 within the top of spout member 20 a combination cap member and pedestal 25 is frictionally received. Member 25 consists of a cylindrical base 26 and a stopper portion 27, the exterior walls of which are slightly convergent from top to bottom as viewed in Figure 5. This stopper portion is adapted to make a sealing fit within cup-shaped portion 24 except at the bottom where, at 28, an enlarged recess is provided in vertical registry with the top of the aperture at 22. When cap 25 is in the position of Figure 5, the fit between stopper portion 27 and cup-shaped interior 24 of spout member 20 is a sealing one. The seal, however, may be readily broken by simply pulling cap 25 vertically away from spout member 20 and tube 10. As soon as this movement is initiated, the complementary sloping walls of the stopper portion and the cup-shaped portion will move out of contact, permitting access of air to the recess at 28. In other words, while stopper portion 27 functions as a seal in the Figure 5 position, it cannot function as a piston when it is removed. Thus, the accidental withdrawal of a substantial quantity of material out of tube 10 incident to removal of cap 25 is prevented.

The recess at 28 in stopper portion 27 provides an enlarged concave dispensing chamber and functions as a dauber or applicator for deodorant cream. This function is accomplished by compressing tube 10 with the parts in the Figure 5 position and thereafter removing the cap member 25, the recess 28 of which will have therein a small quantity of the material to be used. This may be applied directly to the body using base 26 as the handle of an applicator, or, if desired, the portion of the cream in recess 28 may be removed with the fingers and applied in the conventional manner. If any cream is retained within recess 28 the moisture thereof is preserved when cap 25 is restored to the Figure 5 position due to the fact that stopper portion 27 and cup-shaped portion 24 define therebetween a seal. This seal is somewhat augmented in storage due to the fact that under such conditions the tube is inverted as indicated in Figure 4 in connection with another form of the invention, with base 26 resting on a support. This being the case, the weight of tube 10 and its contents and a portion of the weight of spout member 20 is taken on the annular end of stopper portion 27 defining the recess at 28.

The form of the invention illustrated in Figures 6 and 7 again involves the use of a conventional collapsible tube 10 having a frusto-conical end portion 11 and an exteriorly threaded boss 12. In this instance, spout member 29 has a long depending skirt 30 surrounding tube 10 as well as the interior frusto-conical configuration adapting it to fit closely over end wall 11 of tube 10 in direct engagement therewith and the central interiorly threaded aperture at 31 adapted to engage the exteriorly threaded boss 12. At its top, spout member 29 is formed about the outer end of passage defining aperture 31 with an enlarged rounded surface recess 32 for coacting with cap 33 to define an enlarged dispensing chamber in registry with said aperture. This recess is closed by a friction fit cap 33 the flanges 34 of which are interiorly convergent from

bottom to top as viewed in Figure 6. The upper portions of the exterior wall of spout member 29 slope in a complementary manner so that when cap 33 is in closed position it will seal the end of the threaded recess and the top of the operating cavity at 32. As described in connection with the embodiment shown in Figure 5, the complementary slope between the frusto-conical interior walls of the cap and the top exterior walls of the spout member prevent the cap from functioning as a pump when it is moved vertically away from the position at Figure 6. In other words, access of air to the cavity is permitted upon very slight displacement of the cap.

In storage the tube shown in Figure 6 is inverted to rest on the flat surface of cap 33 in the same manner that the Figure 1 assembly is inverted in Figure 4. In use the tube is somewhat compressed after removal of cap 33 so that a body of shaving cream is extruded into the cavity at 32. This cavity is shaped to accommodate the bristles of a shaving brush so that the latter may be coated with cream while the cavity is wiped clean both in a single operation. In the event brushless shaving cream is used, it may be removed from the cavity at 32 either by the fingers or the spout member 29 may be used as an applicator. Regardless of whether the spout member is used as an applicator or whether it is held substantially while material is removed from its upper cavity the convenience of skirt 30 is quite evident, serving as a rigid grip so that the tube may be firmly held without tendency to collapse it.

What is claimed is:

1. In combination, a supporting and material dispensing control attachment for a collapsible tube of the type having an end wall and a projecting discharge nozzle in said end wall comprising a spout member and a sealing cap member frictionally mounted on said spout member, means for securing said spout member upon said tube nozzle, means in said spout member providing a discharge passage through said spout member as an effective continuation of said nozzle, means providing a recess in the surface of one of said members in registry with said passage and of appreciably larger cross sectional area than said passage, said recess being closed by the other of said members so as to provide a reservoir for material squeezed out of said tube, mating conical surfaces on said spout and said cap member terminating in shoulders which are mutually engageable when the cap member is tight on the spout member to positively predetermine the size of said recess, and said reservoir of material being available to a brush or the fingers of a user when the cap member is removed.

2. In the combination defined in claim 1, said recess being formed in the surface of said cap member that overlies the outer end of said passage.

3. An attachment for use with a collapsible tube having an end wall with an apertured threaded boss thereon, said attachment comprising a rigid annular spout having a through passage which is internally threaded for engagement with said boss, said spout having an end wall of such size and shape as to extend substantially over said end wall of the tube in close surface engagement with the latter when the two are in threaded engagement, and a closure member frictionally and removably seated on said spout for sealing said passage, said spout having an enlarged surface recess formed at the outer end thereof of appreciably larger cross-sectional area than said passage and in registry with the outer end of said passage coacting with the adjacent surface of said closure member to define a dispensing chamber for receiving a predetermined charge of material squeezed from said tube, and said chamber being exposed for removal of said charge of material by a brush or the user's fingers when said closure member is removed.

4. In combination, a supporting and material dispensing control attachment for a collapsible tube of the type having an end wall and a projecting discharge nozzle on said end wall comprising a spout member and a sealing cap member frictionally mounted on said spout member, means for securing said spout member upon said tube nozzle, means in said spout member providing a discharge passage through said spout member as an effective continuation of said nozzle, means providing a surface recess in said spout member at the outer end of said passage and of appreciably larger cross-sectional area than said passage, said recess being closed by said sealing cap member so as to provide a predetermined reservoir for material squeezed out of said tube when the cap member is tight on the spout member, and said reservoir of material being available to a brush or the fingers of a user when the cap member is removed.

DONALD E. MARSHALL.
